CLOTHES HANGER BAR FOR A WARDROBE

Ludwig Friedlander, Chicago, Ill., assignor to Chippewa
Paper Products Co. Inc., Chicago, Ill.

Application September 4, 1957, Serial No. 47,597

Term of patent 14 years

(Cl. D33—8)

I claim:

The ornamental design of a clothes hanger bar for a wardrobe, as shown.
